UNITED STATES PATENT OFFICE

165,261

ADVERTISING DISPLAY STAND

Lewis Barry, Upper Darby, Pa.

Application February 2, 1951, Serial No. 14,094

Term of patent 3½ years

(Cl. D80—9)

To all whom it may concern:

Be it known that I, Lewis Barry, a citizen of the United States, and a resident of Upper Darby, Delaware County, State of Pennsylvania, have invented a new, original, and ornamental Design for an Advertising Display Stand, of which the following is a specification, reference being had to the accompanying drawing, forming a part thereof, wherein:

Fig. 1 is a perspective view of an advertising display stand showing my new design; and

Fig. 2 is an end elevation of the same.

The dominant features of my design reside in the portions shown in full lines.

I claim:

The ornamental design for an advertising display stand, as shown and described.

LEWIS BARRY.
